United States Patent Office

Des. 206,787

Patented Jan. 31, 1967

206,787

SHELF UNIT FOR BATHROOMS OR THE LIKE

Robert Z. Lerner, 7 Toppertown Lane, Brookville,
Long Island, N.Y. 10708

Filed July 8, 1966, Ser. No. 3,001

Term of patent 14 years

(Cl. D4—3)

FIG. 1

FIG. 2

FIG. 3

FIG. 1 is a front, top and right side perspective view of a shelf unit for bathrooms or the like, embodying my novel design;

FIG. 2 is a rear elevational view thereof; and

FIG. 3 is a left side elevational view thereof.

The dominant features of the design reside in the portions shown in full lines.

I claim:

The ornamental design for a shelf unit for bathrooms or the like, as shown and described.
